UNITED STATES PATENT OFFICE.

EZRA F. BEAL, OF EVERETT, MASSACHUSETTS, ASSIGNOR, BY MESNE ASSIGNMENTS, TO HIMSELF AND ALONZO DEAN, OF SAME PLACE.

CAR-COUPING.

SPECIFICATION forming part of Letters Patent No. 267,662, dated November 21, 1882.

Application filed July 31, 1882. (No model.)

To all whom it may concern:

Be it known that I, EZRA F. BEAL, of Everett, of the county of Middlesex, of the State of Massachusetts, have invented a new and useful Improvement in Car-Couplings; and I do hereby declare the same to be described in the following specification, and represented in the accompanying drawings, of which—

Figure 1 is an under side view, and Fig. 2, 10 a longitudinal section, of my improved coupling as applied to the platform and draw-bar of a railway-car. Fig. 3 is an under side view, Fig. 4 a top view, and Fig. 5 a side elevation, of the draw-bar and coupling. Figs. 6 and 7 15 are hereinafter described.

The nature of my invention is duly defined in the claim hereinafter presented.

In the drawings, A denotes a draw-bar adapted to slide lengthwise of it in and relatively to the car-platform B, and provided with a spiral spring, C, arranged with it and the platform in manner as represented. Fulcrumed to the draw-bar is a bifurcated lever, D, provided with a link-catch, E, that extends downward from the front arm of such lever into and through the draw-bar and the link-receiving mouth a thereof. The front end of the said arm is beveled, as represented at b, and there is formed in the adjacent lip c of the draw-bar head a recess, d, to receive such end. In the fulcrum-supports e of the draw-bar there are horizontal slots to allow the lever-fulcrum t to slide forward and backward sufficiently for the beveled end of the front arm of the lever to pass into and out of the recess d. Fig. 30 is a side view of one of the said supports e, with its slot, which is shown at f. The two prongs or rear arms, g g, of the lever D embrace a beveled sleeve, F, that, formed as 35 shown, slides on the shank of the draw-bar lengthwise thereof. From each arm g a stud, h, extends toward the draw-bar and directly underneath and against the next adjacent inclined edge i of the sleeve. On moving the 40 said sleeve backward on the draw-bar the arms g of the lever will be depressed, and its front arm, with the link-catch, will be moved upward. From the lower part of the sleeve F a stud, k, extends into a slot, l, made obliquely,

as shown, in a sector, G, pivoted to the draw-bar, the pivot being shown at m. This sector, by a rod, n, is connected with a lever, o, fulcrumed to the car-platform and arranged as represented. The lever extends through the slot p of a locking-plate, H, fixed to the end of the platform, the plate at the ends of the slot being provided with notches q r to receive the lever. A front view of the said plate H is shown in Fig. 7. On turning the lever o from one to the other of the said notches the slot 55 notched sector will be operated so as to cause the sleeve F to move lengthwise on the draw-bar, the movement of the lever one way causing, by means of the sector, the sleeve to retreat on the draw-bar, and thereby to move the lever D in a manner to raise the link-catch in 60 the draw-bar and set free the link for the cars to be uncoupled. When the lever o is in the inner notch of the locking-plate the link-catch will be down within the mouth of the draw-bar. Under this condition of things the link, on being forced into the said mouth, will meet the link-catch (beveled or inclined on its front, as shown at s) and press it upward. As soon as the front-end portion of the link may have 65 passed under and in rear of the catch the latter will fall into the link and couple it to the draw-bar.

With my invention all necessity of going directly between the cars to either couple or 70 uncouple them is avoided; for to enable the link to be drawn out of the draw-bar I have only to lay hold of the front part of the lever o and pull such lever to its outer extreme position. When the said lever is at its 75 inner extreme position the link, on being forced into the mouth of the draw-bar, will couple with the said draw-bar. When the link pulls forward the link-catch the beveled end of the carrying-lever will be drawn into the recess d 80 in the head of the draw-bar, whereby the said catch, with its lever, will be prevented from accidentally being thrown upward so as to disengage the catch from the link. By having the end of the lever beveled and the lever movable rearward relatively to the draw-bar such lever, on the sleeve being forced backward, will 85 readily retreat and pass out of the recess; for

on the front arm of the lever being forced upward the beveled end of the arm, by acting against the inclined upper part of the recess, will cause the lever to move rearward so as 5 to pass out of the recess.

I claim—

The car-coupling substantially as described, arranged and combined, essentially as set forth, with the draw-bar and the car-platform, such

coupling consisting of the link-catch, its supporting-lever, the sliding beveled sleeve, and the slotted sector, adapted as represented, the sector having means of operating it, as explained.

EZRA F. BEAL.
